UNITED STATES PATENT OFFICE.

CHURCH ANDERSON, OF LOS ANGELES, CALIFORNIA.

OIL BURNER FOR FURNACES.

Application filed August 5, 1927. Serial No. 210,770.

This invention relates to an oil burner for a furnace, and an object thereof is to provide a simple, but highly efficient, means for diffusing liquid fuel under pressure into a current of driven air to form a mixture of high quality for use of furnaces and the like.

To that end I provide a means for causing a preliminary mixture formed by a relatively strong discharge of liquid fuel into a minor portion or charge of driven air; and then forming a final mixture by driving the preliminary mixture angling and into the major portion of driven air.

Another object of the invention is to form a mixture of fuel and air by driving both elements through nozzles toward a line that is the longitudinal axis of the nozzles, and then by deflectors interrupt the flow of a portion of the air and all the fuel to form a preliminary mixture and then by additional means accomplish a final mixing of the major portion of the air with the preliminary mixture; to that end I provide rotary deflectors arranged to abruptly throw a portion of the air inwardly toward the longitudinal axis of the nozzles and simultaneously throw all the fuel outwardly from the axis through the deflected or interrupted air, thereby forming a preliminary mixture that is driven on outwardly from the axis to cross into and mix with the major portion of air that is driven on inwardly toward the axis to form the final mixture.

A feature of invention is shown in the construction, combination and arrangement of the various parts whereby an air and fuel mixer is provided that is highly efficient to function with all kinds of liquid fuel to form with air a furnace mixture.

Another feature of invention is shown in the arrangement and mounting of the fuel mixer shaft whereby it is balanced in a single ball bearing. That is, only one bearing is utilized as one end of the mixer shaft telescopes over the end of a motor driven shaft.

Another feature of invention is shown in the construction, arrangement and operation of the parts of the apparatus where they are easy to construct and assemble, compact in arrangement and easy to handle in operation.

A further object is to provide an oil burner that is neat and pleasing in appearance, and strong and durable in use.

Other objects, advantages and features of invention may appear from the accompanying drawings, the subjoined detailed description and the appended claims.

The accompanying drawings illustrate the invention.

Figure 1 is a fragmental plan view of an oil burner for a furnace that is constructed in accordance with this invention showing it hinged to a furnace door; parts illustrated diagrammatically; also showing by dotted lines the oil burner in open position.

Fig. 2 is an enlarged fragmental longitudinal section through the discharge or nozzle end of the oil burner; showing in detail the means for mixing the air and liquid fuel.

Fig. 3 is an enlarged fragmental longitudinal section on line 3—3, Fig. 1, showing in detail the construction and arrangement of parts in the oil burner.

Fig. 4 is an enlarged cross section on line 4—4, Fig. 3.

Fig. 5 is another cross section on line 5—5, Fig. 3.

The oil burner includes an outer housing formed of shells 10 and 11 that are secured together by bolts 12. The shell 10 has its wall 13 extended outwardly and terminated in a flange 14 to which the nozzle 15 is secured by screws 16.

An inner housing 17 is arranged inside of the outer housing and is held centrally therein by a lower pipe support 18 that is preferably integral with both the shell 10 and housing 17.

The housing 17 is recessed at one end for a ball bearing 19 in which the hub 20 of a shaft 21 is mounted. The recess for the bearing is closed by a cap 22 secured to the housing 17 by screws 23; also the recess is enlarged adjacent the ends of the bearing to form a chamber 24 that can be filled with lubricant so that the balls of the bearing will run in oil or grease.

The chamber 24 is filled with oil or grease through an upper pipe 25 that is in communication with an oil cup 26 secured in a boss 27 on the shell 10 and also the purpose of the pipe 25 is to form an upper stabiliz-

ing connection between the inner and outer housings.

The hub 20 is extended and enlarged to form a spindle 28 that is provided with a 5 threaded portion on which the hub 29 of a fan 30 is secured. The spindle is provided with a socket 31 into which one end of a motor shaft 32 is secured so that when the 10 motor 33 is driven the spindle, fan and shaft 21 will be rotated to drive air through the nozzle 15 and also rotate a mixer carried on the end of the shaft.

The construction, mounting and operation of the motor 33 are old and well known in 15 the art and are, therefore, shown only semi-diagrammatically.

The motor is enclosed in a motor housing 34 that is secured to the shell 11 by stud bolts 35. This housing 34 is constructed 20 and arranged so that air taken into the ports 36 will pass over and around the motor to a central opening 37 in the shell 11, shown in Fig. 3, from whence it is driven by the fan 30 through the nozzle 15; and the air flowing 25 over and around the motor will keep it cool.

The housing 17 is also recessed at the other end to provide an oil chamber 38 through 30 which the shaft 21 and also the inner cylinder 39 of a fuel nozzle are extended. The cylinder 39 has a threaded inner end secured in the housing 17 and this cylinder extends loosely over the shaft 21; that is there is a space between the shaft and the inner wall 35 of the cylinder 39.

An outer cylinder 40 has a threaded end 40 secured in the housing 17 and extends over the inner cylinder 39 and is spaced away from it a sufficient distance to form a cylindrical fuel passage 41 that extends from the chamber 38 out through the discharge end of a fuel nozzle formed by the cylinders 39, 40.

The chamber 38 is supplied with fuel oil 45 from a pump 42 driven by the motor 33 semidiagrammatically illustrated in Fig. 1. The pump 42 can be of any rotary type and operated in any well known way to supply fuel to the chamber 38 through a pipe 43 50 that is connected with passage 44 that extends through the support 18, to the chamber.

In other words, the pump 42 is actuated by the motor 33 to force oil through the 55 pipe 43, passage 44, chamber 38 and nozzle passage 41 to spray oil into the passage of air driven through the nozzle 15 by the fan 30 also driven by the motor 33.

Preferably the shaft 21 and cylinders 39, 60 40 are tapered from their cross centers inwardly toward their longitudinal axis so that the orifice at the discharge end of the passage 41 is considerably smaller than the orifice at the inlet end; and so that the discharge 65 of fuel as well as the air driven

through nozzle 15 will be directed toward a predetermined line extending longitudinally and axially through the nozzles.

The shaft 21 has a threaded stem 45 on which a front deflector 46, spider 47, rear 70 deflector 48 and lock nut 49 are secured.

The spider 47 is provided with a ring band 50 to which a mixer shell 51 is secured by rivets 52. The mixer shell 51 is tapered outwardly from its inlet to its discharge end 75 reversely to the taper of the air and fuel nozzles; and all the parts secured to the threaded stem 45 rotate with the shaft 21.

The shell 51 has a thickened inlet end that is beveled to form a deflector surface 53 80 that tapers inwardly toward the center of the deflector 46 so that it deflects a portion of the air passing through the nozzle 15 toward the rotary deflector 46 and across the path of the fuel discharging from the fuel 85 nozzle to thereby form a preliminary mixture of air and fuel. That is, air deflected by the surface 53 will be driven toward the deflector 46 and across the path of the fuel discharging from the fuel nozzle; and the 90 deflector 46 throws the fuel outwardly through the deflected air and against the inner wall of the shell 51 adjacent an inwardly extending shoulder on the thickened end of the shell. 95

The fuel nozzle is arranged to discharge fuel inwardly and angularly against the deflector 46 so that it is splashed in an annular spray outwardly, as stated, against the inner wall of the shell 51 where rotary motion of the deflector 46, spider 47 and coacting with shell 51 accomplishes a thorough mixing of the interrupted or deflected air with the fuel before it passes the deflector 48. 100

This preliminary mixture formed in the 105 chamber between the deflectors 46 and 48 is then forced on; and by means of the rear convex deflector 48 it is forced outwardly away from the longitudinal axis of the nozzles into the major portion of the air that is 110 simultaneously being driven inwardly toward the longitudinal axis of the burner.

Also as seen in Fig. 1 the oil burner is connected to the furnace wall 55 by a hinge 56. The oil burner is held in closed position 115 by means of a forked flange 57 adapted to be fitted over a stud 58 and is held closed by a pin 59.

As thus constructed the oil burner can be held closed or opened to the dotted position 120 shown in Fig. 1 so that the parts are easily accessible for cleaning or repair.

In operation the motor is actuated to drive the fan and pump to force the fuel and a portion of the air into a chamber between 125 the deflectors 46 and 48 to form a preliminary mixture and then form a final mixture of the elements as previously stated.

I claim as my invention:

1. An oil burner for a furnace including 130

- nozzles directed toward a line extending axially and longitudinally through them, means for driving air and liquid fuel through said nozzles, and means adjacent the discharge end of said fuel nozzle for causing a preliminary mixture of the fuel with a portion of the air and then a final mixing of the unmixed air with the preliminary mixture.
- 5 2. The combination set forth in claim 1 and, said means including a rotary shell having a front and a rear deflector between which the preliminary mixture is formed, a spider interposed between the deflectors, and a shaft to which said spider is secured.
- 10 3. An oil burner for a furnace including an air nozzle, a fuel nozzle within said air nozzle, said nozzles arranged to discharge air and fuel toward a line extending axially and longitudinally through said nozzles, a shell tapering outwardly from its inlet end, a thickened inlet end to said shell having an inwardly tapered surface adapted to divert a portion of driven air across the fuel dis-
- 15 20 25 30 35 40 45 50 55 60 65
- charging from the fuel nozzle, a shaft extending through the fuel nozzle and shell, a rotary deflector secured to said shaft adjacent the inlet end of said shell that has a surface tapered outward and arranged at right angle to the tapered surface of said inlet end, a convex deflector secured to said shaft adjacent the discharge end of said shell that is spaced away from said rotary deflector to form a mixing chamber between them, and other means for forming a final mixture of the preliminary mixture and remainder of the air.
4. In an oil burner the combination of an outer housing, a conical air nozzle connected to said housing that is arranged to direct air toward a line that is a continuation of the longitudinal axis of said housing, an inner housing arranged centrally in said outer housing having a fuel chamber therein, a fuel nozzle formed of inner and outer cylinders arranged with an annular passage between them and having tapered ends that are arranged to discharge fuel from the fuel chamber toward a line that is a continuation of the longitudinal axis of said housings, a shaft extending through the fuel nozzle, a tapered shell secured to said shaft, a thickened inlet end to said shell that is tapered inwardly to form a deflector adapted to deflect a portion of the air passing through said air nozzle across the path of fuel discharging from said fuel nozzle, a rotary deflector on said shaft arranged adjacent the discharge end of said fuel nozzle for deflecting the discharge of fuel across the path of the deflected air to thereby form a preliminary mixture and a convex deflector adjacent the discharge end of said shell for the purpose specified.
- In witness whereof, I have hereunto affixed my signature.

CHURCH ANDERSON.
